UNITED STATES PATENT OFFICE.

EDWIN A. ABEEL, OF BERKELEY, CALIFORNIA.

COMB.

Application filed May 10, 1924. Serial No. 712,234.

To all whom it may concern:

Be it known that I, EDWIN A. ABEEL, a citizen of the United States, residing at Berkeley, county of Alameda, and State of California, have invented new and useful Improvements in Combs, of which the following is a specification.

This invention relates to combs, and particularly to a type of comb which may be 10 advantageously used by women wearing comparatively short hair or so-called bobbed cuts.

The object of the present invention is to 15 generally improve and simplify the construction and operation of combs of the character described; to provide means for securing the comb in place so as to avoid displacement and loss; and further, to provide a comb which will not only keep the 20 hair in place when worn, but which may also serve as an ornament.

One form which my invention may assume 25 is exemplified in the following description and illustrated in the accompanying drawings, in which—

Fig. 1 is a side elevation of the comb.

Fig. 2 is a vertical cross-section taken on line 2—2, Fig. 1.

Fig. 3 is a horizontal cross-section taken 30 on line 3—3, Fig. 1.

Fig. 4 is a view similar to Fig. 1 showing one-half of the hook shaped teeth reversed with relation to the other half of the hook shaped teeth.

Referring to the drawings in detail. A indicates the head of the comb, 2 a pair of main end teeth, and 3 a plurality of intermediate teeth. The intermediate teeth are obliquely cut away or slotted on one side 40 as indicated at 4 and a plurality of hooks or barbs 5 are thus formed on one side of each tooth. The intermediate teeth together with the end teeth, are otherwise pointed as indicated at 6 and hook shaped or barb pointed ends are in this manner formed.

The comb as a whole may be slightly bent or curved both vertically and horizontally, as shown at 7 and 8, respectively, in Figs. 2 and 3, and the head of the comb may be 50 finished plain or ornamented as desired.

Combs as ordinarily constructed and worn by women are very liable to become displaced while in use, since frictional engagement of the teeth with relation to the hair

is the only means employed for preventing 55 displacement or loss of the combs.

Combs are very often employed for ornamental purposes and are frequently more or less costly, and it is therefore desirable to provide means, in addition to the mere frictional engagement of the teeth, for preventing accidental displacement or loss of the combs. This is particularly true where 60 combs are worn in short hair or so-called bobbed cuts.

The hooking of the teeth as here shown serves the purpose admirably, as the frictional engagement between the teeth and the hair is materially increased by the added surfaces produced by slotting the points of 70 the teeth, and it should furthermore be obvious that the comb is retained against outward movement by the hooks or barbs formed thereon. In fact, practical experience has proved that it is practically impossible to remove the comb without pulling it 75 endwise through the hair; this being a fairly simple matter where short hair is worn.

While the hooks or barbs, as illustrated 80 in Fig. 1, are formed on one side of the teeth only, it is obvious that the hooks may be reversed with relation to each other, as shown in Fig. 4.

The comb may be constructed of any suitable material, and the finish and proportions thereof may be such as the experience and judgment of the manufacturer may dictate or various uses may demand.

Having thus described my invention, what 85 I claim and desire to secure by Letters Patent is—

1. A comb comprising a head member, a pair of end teeth projecting therefrom, a plurality of intermediate teeth, and hooks formed in the intermediate teeth at their outer ends and in the sides thereof.

2. A comb comprising a head member, a pair of end teeth projecting therefrom, and a plurality of intermediate teeth, said intermediate teeth being pointed and obliquely slotted in one side to form hook shaped outer ends.

3. A comb comprising a head member, a pair of end teeth projecting therefrom, and a plurality of intermediate teeth, said intermediate teeth being pointed and obliquely slotted in one side to form hook shaped outer ends, the hooks on one-half of the teeth be-

ing formed on one side, and the hooks on the other half of the teeth being formed on the opposite side.

4. A comb comprising a head member, a pair of end teeth projecting therefrom, and a plurality of intermediate teeth, each intermediate tooth being angularly slotted in one

side to form side barbs, said barbs lying within the plane of the sides of the teeth and at a point adjacent the outer ends of the teeth and each tooth terminating in a point at its outer end. 10

EDWIN A. ABEEL.
